UNITED STATES PATENT OFFICE.

PETER VILHELM ADOLF AAGE HERBST, OF HOLTE, DENMARK, ASSIGNOR TO F. L. SMITH & CO., OF NEW YORK, N. Y., A CORPORATION OF NEW JERSEY.

TUBE MILL OR BALL MILL.

Application filed August 29, 1925. Serial No. 53,285.

To all whom it may concern:

Be it known that I, PETER VILHELM ADOLF AAGE HERBST, a subject of the King of Denmark, residing in Holte, Geelsvej 15, Denmark, have invented certain new and useful Improvements in Tube Mills or Ball Mills, of which the following is a specification, reference being had to the accompanying drawings, forming a part hereof.

10 This invention relates to tube mills or ball mills, in which the material acted upon is delivered to or from the mill through a hollow trunnion, by which the shell or drum is supported at each end. Such mills are 15 generally rotated by the engagement of a driving pinion on a shaft parallel with the axis of the mill, with a large gear which is mounted directly on the shell or drum of the mill, or on one of the heads thereof. With 20 the continuously increasing demand for safety in the operation of such mills, and in view of the necessity of protecting the wearing parts from the contact of dust, etc., with the gearing and bearings, the driving 25 of the mill through such gearings is not altogether satisfactory. While the gearing may be enclosed or protected to some extent, for the purpose of preventing accidents, it is not possible to make tight joints between 30 the shell or drum of the mill and the casing which encloses the gearing, and it is not possible, therefore, to avoid altogether or to such extent as may be desirable, the passage 35 of dust from the outside within the protective casing or of oil from the bearings and engaging gears within the casing to the outside.

It is the object of the present invention to overcome the difficulties above alluded to, 40 which are incident to the driving of such mills through gearing as described, and in accordance therewith, a driving shaft is placed axially in line with the shell or drum of the mill and is connected through a suitable coupling with the hollow trunnion, which is itself closed at its outer end and is provided in its peripheral wall with suitable openings through which the material may escape.

50 The invention will be more fully explained hereinafter with reference to the accompanying drawings in which several embodiments of the invention are illustrated and in which:

55 Figure I is a view in vertical longitudinal

section through the discharge end of a ball or tube mill and its hollow trunnion and appurtenances, with the driving shaft in elevation.

Figure II is a similar view illustrating 60 a slightly modified embodiment of the invention, in which the driving shaft is coupled to the hollow trunnion through a flexible coupling.

Figures III and IV are detail views in 65 section and on a larger scale illustrating the construction of the flexible coupling shown in Figure II.

Figure V is a view in longitudinal sectional elevation illustrating the application 70 of the driving means to the feeding end of a ball or tube mill.

Figure VI is a detail view in transverse section on the plane indicated by the broken line XX of Figure V. 75

In the embodiment of the invention illustrated in Figures I and II, the head *a* of a tube mill of ordinary construction, except as hereinafter pointed out, is shown as having formed therewith a hollow trunnion *b*, through which material from the shell or drum *c* is discharged, as is well understood, in mills of this character. For convenience in construction, there is secured to the trunnion *b*, which is received 80 in a suitable bearing, a hollow member *d*, which is virtually an extension of the trunnion, such hollow member and the trunnion *b* being conveniently secured together by means of flanges, *e*, *g*, and bolts *f*. The 85 hollow member is closed at its outer end as by a diaphragm *h*, and is provided in its peripheral wall with suitable openings *i*, through which the material discharged from the shell or drum is delivered upon a screen 90 *m*, through which the finer material is discharged into a suitable hopper *n*, while the coarser portions are discharged through a chute *p*. Suitably secured to the delivery member *d*, as by flanges *h* and bolts *j*, is 95 a coupling member *i* which receives in axial alignment with the shell or drum *c*, the end of the driving shaft *q* and is operatively engaged therewith by a key *r*. The screen 100 *m*, which is frusto-conical, is preferably enclosed within a casing *n*, dust excluding joints being provided, as indicated at *s*, *s*.

The embodiment of the invention shown in Figure II is substantially like that shown in Figure I, save in the relations of the de- 110

- livery member or trunnion extension d_1 , the screen m_1 , the discharge chute p_1 and the diaphragms j_2 and k_2 which close the end of the member d_1 . In this instance the coupling member i_1 which is keyed upon the end of the driving shaft g_1 , is operatively connected with the delivery member or trunnion extension d_1 , through the medium of a flexible joint, the construction of which is illustrated in detail in Figures III and IV. As shown, the coupling member i_1 has secured to it a ring z , lugs y of which enter the circumferential channel formed in the flange t of the member d_1 , between spiral springs v which are received in chambers u formed by enlargement of the circumferential slot.
- In the embodiment of the invention shown in Figures V and VI, the driving shaft g_2 20 is coupled to the feeding end of the mill, the head of which is shown at a_2 , through the hollow trunnion b_2 , its extension d_2 and the coupling member v_2 . In this embodiment of the invention, the extension d_2 is formed 25 with feeding openings d_3 , provided internally with radial partitions e_1 and the usual feeding cone c_1 , and is armed exteriorly with scoops f_1 which take the material delivered to the chamber g_1 and discharge it within the hollow trunnion.

It will be understood that the invention can be embodied in other structures which vary more or less in detail from that shown.

I claim as my invention:

1. In a mill of the character described, the combination of a shell or drum, a hollow trunnion by which the shell or drum is supported, the trunnion being closed at one end and provided with openings in its peripheral wall for the passage of material, a driving shaft axially in line with the drum or shell, and a coupling member through which the driving shaft is operatively connected with the trunnion. 40

2. In a mill of the character described, the combination of a shell or drum, a hollow trunnion by which the shell or drum is supported, the trunnion being closed at one end and provided with openings in its peripheral wall for the passage of material, a driving shaft axially in line with the drum or shell, and a coupling member through which the driving shaft is operatively connected with the trunnion, the coupling member being connected with the trunnion through a 50 flexible joint. 55

This specification signed this 12th day of August A. D. 1925.

PETER VILHELM ADOLF AAGE HERBST.
